(57) **CLAIM**

The ornamental design for the pendent lighting fixture, as shown and described.

DESCRIPTION

FIG. 1 is a side elevational view of the pendent lighting fixture in accordance with my design;

FIG. 2 is a top plan view of the pendent lighting fixture in accordance with my design;

FIG. 3 is a bottom plan view of the pendent lighting fixture in accordance with my design; and,

FIG. 4 is a perspective view from above of the pendent lighting fixture in accordance with my design.

The center column, bottom front and boubache include a faux ancient stone finish.

The front, rear, left and right elevational views are symmetrical.

No claim is made to any items appearing in the background of the photograph such as wall plugs and electric cords, and no claim is made to the electric cord extending from the top of the chandelier.
